UNITED STATES PATENT OFFICE

ARTHUR I. RISSEK, OF CHICAGO, ILLINOIS, ASSIGNOR TO U. S. BOTTLE MACHINERY COMPANY, OF CHICAGO, ILLINOIS, A CORPORATION OF ILLINOIS

MACHINE FOR APPLYING THREADED BOTTLE CAPS

Application filed August 1, 1930. Serial No. 472,274.

The invention relates to machines, such as shown in my application Serial Number 354,013, filed April 10, 1929, and Patent Number 1,748,961, dated March 4, 1930, for applying threaded caps to bottles or other containers, and among the objects of the invention is to provide an improved capping head or cap applying member which is adapted to operate in a positive manner especially on the small size caps, and which will pick up the cap aligned in the head, place the cap squarely on the bottle and start the threaded engagement of the cap with the bottle with a light yielding pressure so that the cap will not become cocked or the threads crossed or jammed.

Other objects and advantages will become apparent in the following description, with reference to the accompanying drawings, in which:

Fig. 1 is a section view of the general cap applying mechanism of a turret type of machine, similar to the machine more fully shown in the application mentioned above, this machine being chosen merely for the purpose of illustrating this invention, as the improvements embodied therein and pointed out hereinafter may be used in other types of machines.

Fig. 2 is a plan view of said mechanism with parts broken away, parts omitted, and parts shown in section.

Fig. 3 is a diagram of the operation of the machine.

Figs. 4, 5, and 6 are cross sectional views of the capping head. In Fig. 4 the parts are shown in position for picking up the threaded cap C, corresponding to the position 4 in Fig. 3; Fig. 5 shows an intermediate position indicated in broken lines at 5 in Fig. 3; and Fig. 6 shows the cap fully applied to the bottle B, as at 8 in Fig. 3.

The spider hub 10 and the hub of a cross yoke 11 are fixedly supported in the frame of the machine, as fully shown and described in said application, wherein the corresponding parts are numbered 37 and 41 respectively. The hubs 10 and 11 are in vertical alignment, and in the hub 10 is rotatably mounted the turret shaft 12, which is constantly ro-

tated by a suitable application of power through the bevel gear 14 pinned on the lower end of the shaft 12, which meshes with a bevel pinion 15 fixed on a drive shaft 16. The circular turret bottle support table 18 is pinned to the shaft 12 and rests on the stationary hub 10, thereby supporting the shaft vertically; and to the table 18 are fitted pocketed members 19 for holding the bottles B.

In the fixed hub 11 is keyed a non-rotating support shaft 20, which is bored out to receive the reduced upper end portion 21 of the shaft 12 and is supported on the shoulder 22, formed on the shaft 12.

Keyed on the upper end of the shaft 12, below the reduced portion 21, and supported on a collar 24, pinned on the shaft 12, is a spindle support ring 25 in which the capping head spindles 26 are rotatably and slidably mounted.

Keyed to the shaft 20, against rotation, is a flanged support member 27, which rests on a flat circular seat 28 provided at the center of the member 25, and which has a threaded sleeve 29 extending up around the stationary shaft 20. Resting on the upper surface of the flanged portion of the member 27 is a spur gear 30 which is frictionally held from rotation by being pressed against the member 27 by the flanged ring 31 and hand wheel follower 32 which threads onto the sleeve 29. Then, as the member 25 is turned with the shaft 12, the spindles 26 are rotated by the pinions 34, which mesh with the stationary central gear 30. The pinions 34 are slidably keyed to the spindles and are held between lugs 35 and 36 formed in the member 25.

For moving the constantly rotating spindles up and down and positioning them to pick up, carry, start the threading, and screw the cap down on the bottles B, retained in the pockets 19, as shown diagrammatically in Fig. 3, a cam 40 encircles the spindle support ring 25, and is adjustably supported, for accommodating bottles of different heights, by a screw 41 which threads into the upper end of the shaft 20. The arms of the yoke 42, rotatably mounted on the screw 41, are con-

nected by depending rods 43 to a spider 44, slidably keyed to the shaft 20. To the ends of the radially extending arms 45 of the spider 44, are secured depending bars 46 which are bolted to the upper and lower rings 47 and 471 of the cam 40, the rings being spaced to form the cam groove 48, in which ride the rollers 49.

The rollers 49 are journaled on bars 50 which are slidably guided in vertical grooves 51 in the outer periphery of the ring member 25, and to the lower end of the bars 50 are secured collars 52 which loosely embrace the spindles between a flange 54, integrally formed on the spindle, and a collar 55, slideable on the spindle and connected thereto for rotation by a set screw 56, which engages in a slot 561 in the spindle 26. A ball thrust bearing 57 is inserted between the collar 52 and the flange 54 to reduce friction from the pressure of the spring 60 which is compressed between the collar 55 and the shoulder of an enlarged portion 62 of the spindle. The spindle is hollow, and the extreme lower end 63 is threaded to receive the clamping nut 64, and integrally formed near the lower end of the spindle is a circular flange 65.

The capping head of this invention comprises, generally, a support member 66, a vacuum cup 67, and a solid ring chuck 68. The member 66 consists of a circular flange portion 70, pressed into frictional engagement with the under side of the spindle flange 65 by the nut 64 and antifriction washers 71, 72, 73; and a short hub or sleeve portion 75 spaced below the flange 70 and connected thereto by the arm portions 76. A loose facing ring 77 is inserted between the flanges 65 and 70 so that the head support member 40, 66 is yieldably connected to the spindle for rotation.

The chuck ring 68 is fixedly pressed into a hollow holder 80 which is rotatably connected with the member 66 by pin 801 and held with a limited free axial movement thereto by means of the radial pin 81. The pin 81 is fixed in the hub portion 75 and has an end lug 82 which engages loosely in a notch 83 inside of the stem 84 of the holder, 50 which stem extends through the hub portion 75 and into the enlarged bore 85 in the end of the spindle.

The vacuum cup 67 is loosely mounted within the chuck ring 68, and its outward movement is limited by the flange 86, at the top of the cup, contacting with the upper inwardly projecting surface 87 of the chuck ring.

To the cup 67 is rigidly connected a hollow tube 90 which extends loosely through the bore of the holder stem 84 and is lightly held in any position to which it and the cup 67 may be moved by the spring pressed balls 91 which are inserted in radial holes 92 in the chuck holder 80, and pressed inwardly by the

springs 93 which seat against a band 94 encircling the upper portion of the holder 80.

For creating a vacuum in the cup 67 to pick up a bottle cap, connections are provided as follows: On the upper end of the tube 90 is a spherical nipple portion 96, which enters a conical recess 97 in the lower end of the short hollow plunger 98, forming a universal joint between the tubes 90 and plunger 98. The plunger 98 is loosely disposed in the bore of the spindle above the tube 90 and is lightly pressed into contact therewith by the spring 99 which seats on a shoulder 100 formed in the bore of the spindle, the pressure of the spring 99 being less than enough to overcome the friction of the balls 91 in holding the stem 90 in position.

In the side of the tube 98 is threaded a pipe fitting 102 which projects loosely through a slot in the spindle portion 62 and which is connected by flexible pipes 103 and 113 to a port 104 in the upper surface of the flange member 27, the pipes being connected so that the lower pipe can rotate with the spindle, through suitable cooperating passages 114 in the collars 55 and 52. The member 27 being stationary and the member 25 being in rotation, the member 27 acts as a valve to suitably control the vacuum in the cups 67, in the manner described herein-after. The pipes 113 are connected through passages 106 by controlling grooves 107 in the lower surface of the member 27 to a vacuum line 108; and connected through a similar groove 117 to an open port 109 in the body 100 of the gear 30.

In operation the uncapped bottles B are placed in the pockets 19 as the table 18 rotates, each pocket being in vertical alignment with one of the capping head spindles 26 and the spindle being raised so that the chuck holder is in the elevated position shown at the right in Fig. 3.

The movement is to the left in Fig. 3, and projecting over the bottles in position 4 is a shelf 120 fixed in position, on which the caps are automatically fed from the magazine 121 by the constantly moving belt 122 against a stop 124 on the table. The mechanism is more fully shown and described in said application.

As the spindle moves over the shelf 120 it is lowered by the short depression 125 in the cam groove 48 and again raised as the spindle moves away from the shelf. In normal or starting condition the chuck holder 80 is in its lowermost position, slightly below the position shown in Fig. 4 with the lug 82 engaging the upper end of the notch 83, and the vacuum cup 67 is pulled down so that the flange 86 is in contact with the upper chuck ring surface 87.

Consequently, as the head is lowered over the cap on the shelf, the cup 67 contacts with the top of the cap, the chuck is lowered over

the cap and the cup is connected to the vacuum line. The cup is thereby pressed up into the chuck by the cap, in which position it is retained by the balls 91 as the spindle is 5 lifted to position 5, and the cap is held in alignment in the chuck (Fig. 5), as the cap is carried to position 6, where it is lowered, by the cam depression 126, into contact with the bottle. In this manner displacement of 10 the cap in the chuck is prevented, and perfect alignment when the cap is presented to the bottle is insured.

At position 6 the bottle moves into contact with the belt 127, mounted at the rear 15 side of the turret (Fig. 2), which prevents the bottle from turning in the pockets so that the cap can be screwed down.

At this position the spindle is still held up by the cam dwell 128, so that the cap is rotated under the weight of the chuck and holder alone as the cap is finding the threads on the bottle and starts to move down under the engagement of the threads.

Then, at position 7, when the cap is nearly 25 screwed down, the final cam groove depression 129 to the bottom dwell 130 moves the bar 50 all the way down, compressing the spring 60, so that the final turning is under heavy pressure.

30 After the threading is completed, at position 8, Fig. 3, the spindle is lifted back to the starting height by the cam rise 131, and the vacuum in the cup is not broken until the cup has been pulled as far out of the chuck 35 as it is permitted to move, restoring the parts to normal or starting position, described above.

I claim:

1. In a bottle capping machine, a hollow 40 chuck for applying the cap, a vacuum cup for holding the cap, the cup being slidably mounted in the chuck, yieldable means for holding the cup in positions to which it may be moved in the chuck, and means for producing a vacuum in the cup.

2. In a bottle capping machine, a chuck 45 for applying the cap, a vacuum cup having a stem slidably and rotatably mounted in the chuck, friction means engaging the stem for holding the cup in positions to which it may be moved in the chuck, and means for producing a vacuum in the cup.

3. In a bottle capping machine, a rotatable 55 chuck for screwing the caps onto the bottles, a vacuum cup having a stem slidably and rotatably mounted in the chuck, spring pressed balls mounted in the chuck and engaging the stem of the cup, and means for communicating a vacuum to the cup.

60 4. In a bottle capping machine, a hollow rotatable spindle, a chuck mounted on the end of the spindle, a vacuum cup having a stem rotatably and slidably mounted in the chuck, means for yieldably holding the stem 65 of the cup, a plunger slidably mounted in the

spindle and resiliently pressed into sealing contact with the end of said stem, and means for communicating a vacuum to the cup through the plunger.

5. In a bottle capping machine, a hollow 70 rotatable spindle, a chuck mounted on the end of the spindle, a vacuum cup having a stem slidably and rotatably mounted in the chuck, and having a spherical nipple formed on the end, a plunger slidably mounted in the spindle and spring pressed into contact with the stem, the end of the plunger having a conical recess for receiving the nipple and providing a sealed universal joint, and means for communicating a vacuum to the cup through the 75 plunger.

6. In a bottle capping machine, a rotatable spindle, a chuck mounted on the end of the spindle with a limited axial freedom of movement, a vacuum cup slidably and rotatably 80 mounted in the chuck, frictional means for yieldably holding the cup in the chuck, and means for creating a vacuum in the cup.

7. In a bottle capping machine, a hollow 85 spindle, a chuck slidably mounted on the end of the spindle and frictionally connected thereto for rotation, a vacuum cup having a hollow stem rotatably and slidably mounted in the chuck, means for yieldably holding the stem of the cup in positions in the chuck 90 to which the cup may be moved, a hollow plunger in the bore of the spindle and spring pressed into sealing engagement with the end of the stem of the cup, means for applying 95 a vacuum to the plunger, and means for rotating the spindle.

8. In a bottle capping machine, a spindle, a chuck loosely mounted in the end of the spindle and frictionally connected thereto for rotation, a vacuum cup rotatably and slidably 105 mounted in the chuck, means for frictionally holding the cup in position in the chuck, a cap support shelf, a bottle support, means for rotating the spindle and moving the spindle to lower the chuck over a cap on the shelf, then lift the chuck and lower it over the bottle, and means for creating a vacuum in the cup to pick up the cap on the shelf and carry the cap to the bottle.

9. In a bottle capping machine, a spindle, a chuck loosely mounted in the end of the spindle and frictionally connected thereto for rotation, a vacuum cup rotatably and slidably 110 mounted in the chuck, a cap support shelf, a bottle support, means for rotating the spindle and moving the spindle to apply the chuck to a cap on the shelf, then to carry and apply the chuck to the bottle, and means for creating a vacuum in the cup to pick up the cap, 115 frictional means for holding the cup in the chuck so that the cap is held in fixed relation with the chuck as the cap is carried to the bottle, the vacuum in the cup being released 120 as the chuck is being lifted from the bottle 125 130.

so as to pull out the cup and leave the same in its lowermost position.

10. In a bottle capping machine, a rotatable spindle, a chuck loosely mounted in the end of the spindle and rotatably connected thereto so that the chuck can have a limited axial movement in the spindle, an open ended tube slidably and rotatably mounted in the chuck, means for applying a vacuum intermittently to said tube to retain the cap on the end thereof and means for holding the tube in reeded relation in the chuck so that the cap is held in contact with the chuck.

11. In a bottle capping machine, a rotatable spindle, a hollow chuck loosely mounted in the end of the spindle and rotatably connected thereto so that the chuck can have a limited axial movement in the spindle, a tube rotatably and slidably mounted in the bore of the chuck, means for frictionally holding the tube in position in the chuck, means for moving the spindle to lower the chuck over a cap, and means for applying a vacuum to the tube.

Signed at Chicago, Illinois, this 15th day
25 of July, 1930.
